UNITED STATES PATENT OFFICE.

ORESTE SAMMINIATELLI, OF EAST TOLEDO, OHIO.

COMBINED RAILROAD STEEL TIE AND RAIL FASTENER.

Application filed August 31, 1922. Serial No. 535,461.

To all whom it may concern:

Be it known that I, ORESTE SAMMINIATELLI, a citizen of Italy, residing at East Toledo, in the county of Lucas and State of Ohio, have invented new and useful Improvements in Combined Railroad Steel Ties and Rail Fasteners, of which the following is a specification.

An object of this invention is to produce a steel tie for railway rails and means thereon for clamping the rails thereto.

A further object is to produce a steel tie for railway rails which shall be in the nature of an I beam but which has its lower flange provided with headed edges and transverse elements therebetween to prevent the sinking and longitudinal movement of the tie in the roadbed, said tie having its top flange provided with simple but extremely novel and effective means for clamping the rails thereon.

To the attainment of the foregoing and other objects which will present themselves as the nature of the invention is better understood, reference is to be had to the drawings which accompany and form part of this application.

In the drawings:—

Figure 1 is a top plan view showing rails supported on a tie in accordance with this invention.

Figure 2 is a side elevation, the rails being in section.

Figure 3 is a bottom plan view of the tie.

Figure 4 is a sectional view on the line 4—4 of Figure 1.

Figure 5 is a sectional view on the line 5—5 of Figure 1.

Figure 6 is a top plan view of one end of the tie.

Figure 7 is an elevation of a modified form of clip.

Referring now to the drawings in detail, a steel tie is broadly indicated by the numeral 1. The tie is in the nature of an I-beam, the lower head or flange of which having its edges formed with longitudinally extending depending beads or ribs 2. Between the beads or ribs adjacent the ends of the tie there are transverse ribs 3. By this arrangement the longitudinal movement of the tie when arranged on the roadbed, and the consequent lateral movement of the rails supported on the tie will be effectively prevented. The base of the tie is comparatively broad, which will in itself pre-

vent the sinking of the tie in the roadbed, but the beads or ribs will materially assist in preventing such contingency.

The top flange or head of the tie is, for distinction, indicated by the numeral 4, and preferably has arranged thereon, at the portions thereof on which the rails 5 rest, cushion blocks 6 which serve to absorb the shocks to which the tie would be otherwise subjected when the wheels of the rolling stock pass over the rails.

On the top 4 of the tie I secure clips. For distinction, the inner clips are indicated by the numeral 7, and the outer clips by the 70 numeral 8. A pair of clips is disposed at opposite sides of the rail 5, the inner clips 7 being really in the nature of rail clamps, the same having their body portions straight, their inner edges, cut at an upward inclination, as at 9, the central portion of the said inner edges concaved, as at 10 whereby a pair of rail engaging lips 11 respectively are provided at the said inner edge of the rail 75 engaging clips 7. It is, of course, readily understood that the lipped portions of the member 7 have their inner faces conforming to the shape of the base flange of the rails and are in contacting engagement with both the upper surfaces and edges of the said base flanges. I have termed the rail engaging members 7 clips, for the reason that the same have their ends provided with inwardly directed flanges 12 which are designed to underlie the top of the tie 1, while securing 80 means 13 pass through the lips and through the flanges for forcing the lips in tight engagement with the rails and the flanges in tight engagement with the under face of the head of the tie. The rail engaging clips 7 85 have their outer edges provided with longitudinally extending grooves 14.

One pair of outer clips is arranged on the tie at a different angular relation with respect to the rail from that of the opposite pair of said clips. Each pair of clips 8, however, have their inner edges grooved longitudinally, as at 15 and have their ends provided with inwardly directed flanges similar to the flanges 12 on the clips 7 disposed below the head of the tie, while there is passed between the clips 15 and the flanges 16 thereof securing means 17, which tightly bind the clips on the rails. Between the bodies of the opposed clips 8 and the rail engaging clips or clamps 9 there are provided 100 opposed V-shaped passages through which

are passed wedge keys 18. The wedge keys have their edges provided with tongues 19 that are received in the grooves of the elements 7 and 8. The bodies of the wedge keys, adjacent their reduced ends are provided with a plurality of spaced and preferably staggered apertures 20. Through one of these apertures and in contacting engagement with the edge of the head of the tie there is passed the shank of a headed member 21, the said shank being provided with transverse apertures through one of which there is passed a holding element preferably in the nature of a cotter pin 22.

13. If desired, the clips may be each constructed in sections as disclosed in Figure 7 of the drawings. The upper or main section is recessed, as at 14 to provide a rail engaging lip. The body of the upper section may be centrally notched, but its straight outer ends, 24, are contacted by the straight faces on the rounded ends of the removable sections 12'. Securing means 13' pass through the lower hook members 12 and through the upper member of the clamp.

As disclosed in Figure 6 the edges of the flanged top of the tie 1 are cut-away, as at 23 for a distance equalling the space on the tie occupied by the clips, wedges and rails so that when sectional clamps are employed, the inner walls of the portions 12' thereof will contact with the outer walls provided by the said cut-away portions and the outer or end clamps will also contact with the shoulders provided by the end walls of the said cut-away portions 23.

The openings through which the means that secure the clamp 7 on the tie pass are elongated, but the openings through which the retaining elements for the clips 8 pass are round so that movement of these ele-

ments will be prevented when the securing means therefor is passed therethrough, see Figure 6. This permits the wedge members being forced entirely home before the securing elements for the clips or clamps 7 are likewise driven home, and as a matter of fact, the last mentioned elements need not be wholly moved to such position as the fixed engagement between the members 7 and 8 caused by the wedges will hold the clamps 7 at all times in rail engaging position.

Having described the invention, I claim:—

A metal tie and a means for securing rails thereon, said tie being in the nature of an I-beam and having the edges of its head notched longitudinally, cushions on the head on which the rails rest, rail engaging clips having their inner edges beveled inwardly to engage the base flanges of the rail and being centrally notched to provide spaced lips, inwardly directed flanges on the ends of the clips, binding means passing through the clips, the flanges thereof and the head of the tie, said clips having their outer edges grooved longitudinally, clips having inwardly directed flanged ends received in the notch of the tie head and contacting with the end walls thereof are disposed angularly with respect to the clips, means securing the clips on the tie, said clips having their inner edges grooved longitudinally, wedge keys having longitudinal tongues received in the grooves of the opposed clips, each of said wedge keys having staggered apertures therethrough, a headed element having its shank passing through one of the apertures and contacting the edge of the tie, and a cotter pin passing through one of said apertures.

In testimony whereof I affix my signature.
ORESTE SAMMINIATELLI.
